UNITED STATES PATENT OFFICE.

SEBASTIAN GAUL, OF WYCKOFF, NEW JERSEY.

WOODWORKING CLAMP.

Application filed June 1, 1928. Serial No. 282,099.

The subject-matter of the present invention relates generally to the woodworking art, and the improvements are directed to a novel form of clamp for facilitating the union of a plurality of strips of wood, such as boards, to form panels, or the like.

One of the important objects of the invention is the production of a clamp of the above-mentioned character embodying a pair of frame members having their flanges interrupted to define spaces for the reception of certain adjustable elements.

Another object is to provide means in the form of a pair of adjustable elements, carried by the flanges of said frame members, and adapted to be positioned at various locations therealong for the purpose of accommodating the different widths of panels to be clamped.

Still another object of the invention is the provision of certain locking means, associated with one of the adjustable elements, and adapted to cooperate with certain notches arranged in one of the flanges of said frame members for positively maintaining said element in a definite fixed position.

A still further object is the provision of adjustable elements, each being suitably recessed to cooperate with one of the flanges of the frame members in slidable engagement, and to coact with the web portions of the said members to permit the assembling and convenient removal of the latter.

Another object of the invention is to provide frame members similar in construction, and adapted to cooperate with certain adjustable elements to permit the superimposing of said members in stack formation.

With these objects in view, together with others, which will appear as the description proceeds, the invention resides in the novel formation, combination and arrangement of parts, all as will be described more fully hereinafter, illustrated in the drawings, and particularly pointed out in the claims.

In said drawings:

Fig. 1 is an elevation of my novel and improved clamp.

Fig. 2 is a top plan view thereof.

Fig. 3 is an enlarged end elevation of the clamp as viewed at the left of Fig. 1.

Fig. 4 is an enlarged sectional view, taken on the line 4—4 of Fig. 1.

Fig. 5 is a similar sectional view, taken on the line 5—5 of Fig. 1 and illustrating the front end of the clamp in elevation.

Fig. 6 is a transverse section, slightly enlarged, and taken on the irregular line 6—6 of Fig. 1, to depict the notches and spaces in the frame members.

60

Fig. 7 is a detail view of the block positioned at one end of the frame members, and detached from the same to illustrate the recesses therein; and

Fig. 8 is an elevation of a plurality of 65 clamps arranged in stack formation, the series of boards clamped thereby being shown in dot and dash lines.

Before presenting the invention in detail a brief synopsis of the same will be set forth 70 in order that the features and salient advantages thereof may be clearly understood. Accordingly, each clamp in its simplest form, and as shown in Fig. 1, will embody a pair of frame members 10 and 11, exactly similar in 75 construction, and maintained in spaced relation by adjustable elements 12 and 13, termed the reciprocatory follower and head respectively, and a fixed block 14, each of these parts being somewhat similar in construction 80 and adapted to cooperate with the frame members in the fulfillment of the objects aforesaid.

At this time it is pointed out that while 85 Fig. 1 indicates the provision of a pair of frame members for each clamp, it will become apparent hereinafter that novel means is provided whereby each frame member will carry adjustable elements, adjacent the top and bottom portions thereof to permit the 90 superimposing of said frame members in spaced relation.

Referring now in detail to the construction 95 of said frame members it will be observed on inspection of Fig. 3, that each is provided with top and bottom flanges 15 and 16 connected by a web 17, said top flange 15 extending continuously along the length of said frame member and being provided with a plurality of notches 18 arranged in spaced relation in one leg of the flange 15, as indicated in Fig. 6. The bottom flange 16, however, is interrupted at intervals to define spaces or gaps 19, positioned oppositely from the base portion of said web 17, (see Fig. 6), while the 105 interruption at one end of the frame member is increased to present a relatively long space 20 for an appreciable reciprocation of said follower 12, as will presently appear.

The adjustable elements 12 and 13, and the 110 block 14 are formed to cooperate with the flanges of the frame members and the gaps

and spaces provided therein, and when assembled in the position indicated in Fig. 1 will space the frame members a suitable distance apart to receive certain widths of boards directly clamped together by said head 13 and follower 12. In order to accommodate different widths of the boards, these elements are variable and may be made in different sizes to meet all demands. This feature is mentioned to show the susceptibility of the clamp to accommodate itself to the particular work to be performed.

The detailed showing in Fig. 7 of the block 14 may be cited as a typical example of the arrangement of recesses therein, and it will be noted a vertical recess 21 extends downwardly from the top edge of the block and that the bottom portion is provided with a substantially T-shaped groove 22 having a restricted neck 23 alined with said recess 21. Each of the follower and head members are provided with similar recesses and grooves and are provided with like numerals. Said block 14 is adapted to be fixedly secured to said frame members 10 and 11 by means of suitable fastening means 24 and 25, (see Fig. 1), after said recess 21 is fitted with the web 17 of member 10 at one end of the space 20, at which point, it will be recalled, the flange 16 was interrupted or removed. Said T-shaped groove 22 conforms to the flanges 15 of the frame members and in this particular instance will be inserted thereover, the neck 23 lying contiguous to the web portion just below the flange 15 of the member 11. By preference the upper portion of said block is shouldered, as indicated at 26, (Figs. 1 and 5), which abuts the bottom face of the flange portion adjacent the end of said member 10. The above manner of attaching or assembling the block is similar with respect to each of the follower and head members, 12 and 13, respectively, with the exception that the upper portions 12^a and 13^a of each, formed by producing shoulders 12^b and 13^b, are equal in width to said gaps 19 and hence are snugly fitted therein. In assembling the parts just described, they will each be inserted along the top flange 15 of the frame member 11, whereupon the frame member 10 may be literally dropped into the recesses 21 at the gaps 19.

As indicated by the dot and dash lines in Fig. 8, the series of boards forming a panel will have their top and bottom surfaces snugly contacted by the faces of the flanges 16 and 15 of members 10 and 11 respectively, while the longitudinal edges of said panel will abut the head 13 at one side and the follower 12 at the other during the clamping operation. In order to accommodate the clamp to varying widths of panels the head 13 may be engaged with its upper portion 13^a in a selected gap 19 by releasing the spring-pressed dog 27, (see Fig. 2) and sliding the head to the desired position whereupon the nose of said dog

engages in a notch 18. It will be observed that the accurate arrangement of the gaps 19 and notches 18 with respect to each other permit the positive positioning of the head 13. After the head has been properly located said follower 12 is retracted along the space 20 by operating the non-travelling screw 28 by means of crank 29, said screw being threadedly engaged in the block 14, as clearly shown in Fig. 1, and manifestly the rotation of the crank 29 in the opposite direction to the retracting of the follower 12 causes the latter to abut the contiguous edge of the panel and firmly clamp the same in the device. In view of the tight binding action of the head 13 and the accurate spaced parallelism of the frame members, all tendency of the series of boards to bulge and distort out of horizontal plane, is reduced to a minimum. When a single clamp is used frame members 10 and 11 are used as shown in Fig. 1 and the boards are placed between the head 13 and follower 12, said head 13 being positioned in a selected gap 19 and notch 18, as aforesaid, while the follower 12 may assume any position along said space 20, depending of course upon the particular width of the panel.

As shown in Figs. 1 and 4, said follower 12 is provided with a bore 30 to receive one end of said screw 28 which is annularly grooved, as indicated at 31, for the reception of a headless screw 32 threadedly passing through aperture 33 in said follower. Said screw 32 enters from the top surface of the shoulder 12^b and may be removed by elevating the frame member adjacent thereto for the release of the non-travelling screw 28 as desired. While not absolutely essential I prefer to loosely mount the crank 29 on the end of the screw 28 and to provide its hub portion with teeth 34 adapted to engage a similarly formed member 35 fixedly carried by said screw 28. The engagement with member 35 is effected by sliding the crank on said screw to operate the latter and when the clamping operation is finished the crank may be retracted to remain in a pendent position during the drying of the panel. This feature is of importance in instances where the clamps are arranged in stack formation as shown in Fig. 8, since the cranks may remain in a pendent position and thus take up a small amount of space. The spring-pressed dog 27 is preferably pivoted in a grooved boss 36 extending laterally of said head 13, as shown in Figs. 3 and 6.

The idea of constructing the frame members in a similar manner permits the assembling of the same to present literally a plurality of clamps, and as clearly shown in Fig. 8, each of the heads 13, the followers 12 and blocks 14, being arranged in pairs, vertically disposed, and cooperating with the flanges of a frame member so that the T-grooves 22 may engage flange 15 and the recesses 21 en-

gage the bottom flange 16. In view of this specific arrangement it is not necessary to use a pair of frame members for each clamp, since one frame member may become the top frame member of one clamp, and the bottom frame member of the clamp thereabove. This construction will be readily understood on inspection of Fig. 8.

In Fig. 8 of the drawings, the heads 13 and 10 followers 12 are shown in similar positions and the series of boards therebetween appear to be substantially the same width. This may be considered an ideal position, but it will be understood that in actual practice the heads 15 13 will be presumably in a staggered relation in selected gaps 19, and the followers 12 will be arranged in positions along the space 20 in accordance with the particular width of a panel clamped thereby.

20 While the present is a disclosure of the preferred embodiment of the invention, it is to be understood that the same is not limited thereto, as various changes in the minor details of construction, proportion and arrangement of parts may be resorted to without departing from the spirit of the invention as 25 defined in the appended claims.

Having thus described my invention, I 30 claim as new and desire to secure by U. S. Letters Patent:

1. A clamp of the character described, comprising frame members each presenting top and bottom flanges, a block adapted to be fixedly secured at one end of said members 35 and to maintain the same in spaced relation, a head carried by the other ends of said members and adapted to be adjustably positioned thereto, and a follower member positioned intermediate said block and said head and 40 adapted to be reciprocated to clamp material positioned between the same and the head.

2. A clamp of the character described, comprising a pair of frame members each presenting top and bottom flanges, each of the 45 latter flanges being interrupted to define spaces, a recessed head adapted to fit over the top flange of one of the frame members and to fit into a selected space in the bottom flange of the companion frame member, a follower 50 member similarly associated with said frame

members and means for reciprocating said follower member.

3. A clamp of the character described, comprising a pair of frame members each presenting top and bottom flanges, the bottom 55 flanges of each of said members being interrupted to present gaps therealong and to define a relatively long space adjacent one end of said members, a head having recesses and adapted to be fitted over the top flange of one 60 of the members and to be engaged in a selected gap in the other frame member, an apertured block fixedly carried by said members, and a reciprocatory follower presenting recesses 65 for coupling with the flanges of said frame members and adapted to cooperate with said head for clamping material therebetween.

4. A clamp of the character described, comprising a pair of frame members each presenting top and bottom flanges, the bottom 70 flanges of each member being interrupted to define gaps and a relatively long space adjacent one end of the members, the top flanges of said members presenting notches, a follower member having a T-shaped groove for 75 insertion over the top flange of one of the members and having a recess for the insertion of the web of the other member adjacent the long space therein, a head presenting recesses for engagement with the top flange of 80 one of the frame members and for engagement with the spaces in the bottom flange of the other member, spring-pressed means associated with said head and adapted to be inserted in a selected notch and means for reciprocating said follower for clamping material 85 between the same and said head.

5. A clamp of the character described, comprising frame members each presenting top and bottom flanges, a block adapted to be 90 fixedly secured at one end of said members to maintain the same in spaced relation, a head arranged at the other end of the members, means for locking said head in a selected position, a follower positioned intermediate said 95 block and head, and means for reciprocating follower to permit the clamping of material between the same and said head.

In testimony whereof I affix my signature.
SEBASTIAN GAUL.
